H. A. MELAT

POLISH ROD GRIP

Filed Nov. 13, 1924

Inventor
HENRY A. MELAT

By *A. L. Jackson* Attorney

UNITED STATES PATENT OFFICE.

HENRY A. MELAT, OF FORT WORTH, TEXAS.

POLISH-ROD GRIP.

Application filed November 13, 1924. Serial No. 749,786.

My invention relates to polish rod grips for use in pumping operations; and the object is to provide a simple gripping device which will act with certainty and which will not become detached or loose in operation and which has a tendency to become tighter on the polish rod during operation. Another object and advantage is that the device is easily and readily installed and detached and the two parts will remain assembled when detached. Other objects and advantages will be fully explained in the following description, and the invention will be more particularly pointed out in the claims.

Reference is had to the accompanying drawings which form a part of this application.

Fig. 1 is an elevation, showing the grip assembled and engaging a polish rod. Fig. 2 is an enlarged plan view of the gripping members. Fig. 3 is a front elevation of the same. Fig. 4 is a perspective elevation. Fig. 5 is a perspective view of the gripping members, showing the relative position of the polish rod.

Similar characters of reference are used to indicate the same parts throughout the several views.

The improved grip has a body member or shoe 1 provided with a vertical opening 2 for the wedge or clamp 3 and the opening 2 is tapered from the upper end downwardly corresponding to the taper of the wedge 3. The wedge 3 is concavo-convex in form, the concave side engaging the polish rod 4. The body member or shoe 1 has a slot 5 in the front side to receive the polish rod 4, this slot 5 opening into the vertical opening 2. The wedge 3 has a head 6 for convenience in installing and detaching the grip. The wedge may be driven downwardly for clamping the polish rod 4 by hammering on top of the head and it may be driven upwardly for detaching the wedge from the polish rod by hammering on the underside of the projecting head. The wedge will not become loose in operation because the tendency of the wedge is to become more firmly pressed against the polish rod.

The grip is provided with a body having sockets 7 for the pumping cable 8. These sockets are relatively of large diameter at

the bottom and taper upwardly, as shown in Figs. 2 and 3. By such construction, the rope or cable will not become detached from the body or shoe because the tendency will be to make rope tighter in the sockets.

Fig. 1 illustrates the several parts in action. The cable 8 extends upwardly and is looped over the walking beam 9 for action. The polish rod 4 is shown extending down into the pump and casing head.

When the grip is not in use, the wedge will not fall out of the shoe 1 because the wedge is wider than the slot 5 and the head 6 will not pass down through the shoe because the head will be caught on the shoulders 10. The grip can be readily adjusted on the polish rod at any required height by loosening the wedge and then moving the grip to the required position and then tightening the wedge.

What I claim, is,—

1. A polish rod grip comprising a body member having a vertical opening there-through tapered on one side and curved concave on opposite sides and one side engaging the polish rod, a wedge having concavo-convex surfaces corresponding to the convex surface of the rod and the concave surface of said body member and a tapered surface for engaging the tapered surface of said body member, said body member having a vertical slot for insertion of a polish rod into said vertical opening, and a head on said wedge projecting laterally beyond the vertical surface of said body and serving as a means for adjusting said wedge.

2. A polish rod grip and cable holder comprising a body member having a vertical opening concave on opposite sides and one of said concave sides being tapered, and said member having a vertical slot opening into said tapered side forming shoulders on opposite sides of the slot, and a wedge having a concave side for engaging a polish rod and having the other side convex and tapered for engaging the concave tapered surface of said opening and having a head projecting beyond the vertical edge of said body for adjusting purposes and for resting on said shoulders when the grip is not in use.

3. A polish rod grip and cable holder comprising a body member having a vertical

opening concave on one side for engaging a polish rod and concave and tapered on the other side for engaging a wedge and having a vertical slot opening into the tapered side of said opening and having a laterally projecting head for adjusting purposes, and rope sockets formed on said body member for a pumping cable. 10

5 of said opening, a wedge having a concave side for engaging a polish rod and a convex tapered side for engaging the concave ta- In testimony whereof, I set my hand, this 8th day of November, 1924.

HENRY A. MELAT.
